UNITED STATES PATENT OFFICE.

THEOPHILE H. WILSON AND EARL R. MALTBY, OF BUFFALO, NEW YORK.

ROOF COVERING.

Application filed November 23, 1918. Serial No. 263,869.

To all whom it may concern:

Be it known that we, THEOPHILE H. WILSON, a citizen of the United States, and EARL R. MALTBY, a subject of the King of Great Britain, residing at Buffalo, in the county of Erie and State of New York, have invented certain new and useful Improvements in Roof Coverings, of which the following is a specification.

10 This invention relates to roof coverings, and more particularly to shingles or covering units, preferably formed of asphaltic or other compositions.

One of the objects of our invention is the 15 production of shingles or covering units so formed that when laid upon a roof they will be so exposed to the weather that winds blowing at an angle will come in contact with the lower edges and one of the adjacent 20 side edges of the shingle or unit and be deflected thereby so as to avoid the tendency of the wind lifting the shingle or unit from its support.

Another object is the provision of a shingle 25 so formed that it will cover a space at least double that covered by an ordinary shingle and so that each shingle will form part of two rows or courses.

Another object of our invention is the production of a simple and durable shingle or 30 covering unit which may be formed from any suitable composition and which is constructed of two offset parts having the appearance of two separate and distinct 35 shingles arranged in offset relation and joined together at the sides, and when applied to a roof or other foundation, the lower end of one of the parts of each shingle or unit is included in one course of shingles or units and spaced from corresponding 40 parts of adjacent shingles or units, each shingle or unit having a portion exposed between the lower ends of adjoining shingles or units in the course above so that each 45 shingle or unit has a Z-shaped exposed portion giving the appearance of a thatched roof, with the advantage that all joints are more effectively broken than with ordinary shingles.

50 A still further object is the provision of a shingle or covering unit which may be used to equal advantage on roofs or the sides of buildings, owing to the spaced arrangement of the lower ends of one of the parts 55 of each shingle with reference to adjacent shingles.

A still further object of our invention is the provision of a shingle or covering unit having a wide medial or body portion and two oppositely-directed extensions offset with respect to each other, thus forming two connected offset parts, one of the parts of which when applied to a roof or other foundation in conjunction with like shingles or units forms a gage for the next course of shingles, thereby eliminating the use of straight edges or chalk lines, which results in a considerable saving of time and labor in securing the shingles in place.

A still further object is the provision of a covering unit so formed that when laid to cover a surface, all joints will be effectively broken; also that the minimum quantity of material will be employed for each unit, since useless parts covered by overlying units in roof coverings now in use are dispensed with, the material so employed in other roof coverings being utilized in our invention to form a portion of another covering unit.

A still further object of our invention is the provision of a roofing unit having staggered extensions at its upper and lower edges, the unit being reversible so that either edge may be used for the exposed portion of the unit.

Our invention consists in the construction, combination and arrangement of parts to be hereinafter described and more particularly set forth in the subjoined claims.

In the drawings:

Fig. 1 is a plan view of a portion of a roof showing our improved shingles or covering units applied thereto.

Fig. 2 is a vertical section taken on line 2—2, Fig. 1.

Fig. 3 is a perspective view of a portion of a building having a sloping roof to which a number of shingles or covering units constructed according to our invention are applied.

Fig. 4 is a perspective view of a modified form of our improved shingle or covering unit.

Referring now to Figs. 1, 2, 3 of the drawings, the reference numeral 5 designates the roof foundation, and 6 a strip of roofing material applied to the lower marginal portion of said foundation and being preferably formed of the same material as that used in the construction of our improved shingles, owing to portions of this strip material be-

ing exposed, as will be explained herein-after.

7 designates our improved covering unit. In its broader sense, each unit has a body portion 7^a with an extension or extensions 22 at its upper edge and an extension or extensions 23 at its lower edge. The extensions 22 at the upper edges of the units are offset with respect to the extensions 23 at the lower edges, and more specifically describing the construction of the unit shown in Figs. 1 to 3, in which each unit is in the form of a duplex shingle, each shingle consists of two parts 8, 9, of equal lengths offset as at 10 so that the part 8 extends above the upper edge of the part 9 and said part 9 extends below the lower edge of the part 8. Each shingle or unit has therefore two offset upper edges 11, 12; two offset lower edges 13, 14; two offset right hand edges 15, 16, and two offset left hand edges 17, 18, one of the right hand edges being preferably in line with one of the left hand edges of the shingle or unit, these two last-mentioned edges being spaced apart by the offset continuation 10 of the two parts of the shingle or unit.

The shingle or unit, while having its parts of rectangular formation, may be otherwise shaped if desired. One of the members or parts of each shingle or unit has its lower right hand end joined to the upper left hand end of the other member or part so that a portion of one member or part extends upwardly beyond the upper edge of the other member or part and a portion of said other member or part extends downwardly beyond the lower edge of the first-mentioned member or part. Each shingle or unit may be said to be of Z-formation adapted to be applied to a roof or other foundation, by placing the height of the Z horizontally.

When applying shingles or covering units constructed according to this invention, to a roof or other foundation, the strip of roofing material 6 is applied to the lowermost part of the foundation and is adapted to be partly covered by at least the first course of shingles or units to be applied to the foundation. After this strip of material is fastened in place the first course of shingles or units is applied over said strip with the upper portion of the part 9 of each shingle or unit in contact or in close proximity to the lower portion of the part 8 of the adjoining shingle or unit. With these shingles or units applied to form the lowermost course, the lower portions of the parts 9 of all shingles or units in this course are spaced apart and the lower edges of the part 8 of said shingles or units form a gage line for the next course of shingles or units.

As clearly shown in Figs. 1 and 3, the

strip of roofing material 6 is exposed through the spaces between the lower portions of the parts 9 of the various shingles or units of the first course and may therefore be said to form part of the first course. The next course of shingles or units is then fastened in place with the lower edge of the part 9 of each shingle or unit aligned with the lower edges of the parts 8 of the first course of shingles or units, the right hand edge of the part 9 of each shingle or unit being positioned in a line passing medially through the part 8 of one of the shingles or units in the first course while the left hand edge of the part 9 of each shingle or unit is positioned in a line passing medially through the part 9 of a shingle or unit in the first course, thus the joints between the shingles or units of the first course are beneath and equal distances from the side edges of the exposed portion of the part 9 of the second course. In this manner Z-shaped portions of the shingles or units of the first course are exposed and both side edges of the lower portions of part 9 of each shingle or unit and the lower edge thereof are exposed so that winds blowing obliquely against the shingle-covered roof or other structure will come in contact with the corners of the shingle or unit and be deflected thereby both upwardly along one of the side edges of the lower portion 9 and also along the lower edge thereof, thus minimizing the tendency of the shingles lifting from their places.

The shingles or units may be nailed in place as indicated at 19, or in any other manner. It will be apparent from the foregoing, that each shingle or unit forms equal parts of two courses of shingles or units, and that when laying one course, one-half of the course above is laid at the same time. It will also be apparent from the dotted lines in Fig. 1 that all joints are broken and that the shingles or units are fully lapped so that a weather-proof covering is provided, and that owing to the zig-zag or Z-shape exposure given each shingle or unit the roof or other foundation covered is given a thatched appearance.

In the modification shown in Fig. 4, the principle of our invention is embodied in a slab or unit 7^a having double covering area of the shingle or unit disclosed in Figs. 1 to 3. The shingle or unit shown in Figs. 1 to 3 may be considered a duplex shingle or unit, while that disclosed in the modified form shown in Fig. 4 may be termed a quadruplex shingle or unit, but the principle of our invention may be extended to form a sextuplex shingle or unit or be increased to any desired width so as to cover any area of the roof, including even roll material. In the use of a multiple covering, such as shown in Fig. 4, the lower project-

ing portions 20, which correspond with the lower portions 23 of the parts 9 of the duplex shingles or units shown in Fig. 1, are applied to the roof in the same relation to 6 parts beneath as said lower portions 23 of the parts 9 shown in Fig. 1, and this will automatically position the parts 21 projecting upwardly in the same relation to other parts as the upper portions 22 of the parts 10 8 of the shingles or units shown in Fig. 1. Thus the multiple shingle or covering unit shown in Fig. 4, or any enlargement thereon, will form portions of two courses of covering material in the same manner as the 15 shingles or units shown in Figs. 1 to 3 form parts of two courses of shingles or units.

While the shingle or roof covering constructed according to our invention is intended to be formed of composition material, it is nevertheless to be understood that it can be formed of wood or any other material, and while we have shown the two offset parts of a shingle or covering unit or the lower offset marginal regions of the 25 covering material forming this invention of rectangular outline, it may, in some instances where a highly ornamental covering is desired, be found advantageous to change the outline of the lower ends of the two 30 parts of the shingles or units, or the lower offset regions of the covering material. It is also to be understood that the length of the downwardly projecting portions of the shingle or covering material may be varied, 35 depending upon the degree of exposure to be given the course when laid.

It is also to be understood that by forming an extension at the upper edge and at the lower edge of the duplex shingle, or by 40 forming extensions at the upper edge and the lower edge of the slab or strip, such parts may be conveniently reversed so that either the upper marginal portion or the lower marginal portion of the same may serve 45 as the exposed part when applied to a roof.

While our invention is entitled "roof coverings", and although in some of the claims we have also used this term, we desire 50 it to be understood that this term is not used in a restrictive sense, since the invention is adapted for covering side walls of buildings or other structures, or to be used for any purpose for which shingles or roofing material are now used.

Having thus described our invention, what we claim is:—

1. A duplex shingle comprising two oblong parts offset lengthwise to provide a projecting portion at each end of said shingle so as to permit of exposing either end when the shingle is laid.

2. A roof formed of covering units, each unit comprising a body portion notched at its upper and lower edges to form extensions on said edges and having the notches

and extensions at both edges of equal area, the notches and extensions at one edge of aligned units being staggered with reference to the notches and extensions at the other edge, said units being laid so that each 70 forms part of two courses on a roof or the like.

3. A roof covering comprising overlying units, each unit having a body portion provided with a plurality of integral parts, 75 each part being substantially rectangular, certain of said parts having upwardly-directed extensions and the remaining parts having downwardly-directed extensions offset with respect to said upwardly-directed 80 extensions, said units being laid to expose Z-shaped portions of underlying units.

4. A duplex shingle comprising two oblong parts offset lengthwise, each of said parts being of equal width and joined along 85 a straight imaginary line centrally between the side edges of the shingle, the offset portions permitting the shingle to be reversed.

5. A duplex shingle of a given width comprising two integral offset parts, each 90 part having a given length and being one-half the width of the complete shingle, one part extending in the direction of its length above the other part and said other part extending in the direction of its length below 95 said first-mentioned part so as to permit the shingle to be reversed.

6. A duplex shingle having an extension at its upper end and an extension at its lower end and being reversible end for end. 100

7. A duplex shingle having like offset oblong portions and either end of which may be used as the bottom or exposed portion of the shingle.

8. A roof covering comprising a plurality 105 of overlying units, each unit having a plurality of extensions along its lower edge separated by notches, said extensions and notches being substantially of equal width, said units to be laid so that opposite side 110 edges of each extension are respectively in line with the center of an extension and the center of a notch of the unit beneath.

9. A roof covering comprising a plurality 115 of overlying units, each unit having a body portion and an extension at the lower edge of said body portion, the lower exposed edge of said body portion and the lower edge of said extension being of substantially equal lengths, said units being laid with the lower exposed edge of the body portion of each unit in line with the lower edge of the extension of an adjoining unit and with one of the side edges of said extension in line with the center of the extension of the unit 120 beneath.

In testimony whereof we affix our signatures.

THEOPHILE H. WILSON.
EARL R. MALTBY.
